UNITED STATES PATENT OFFICE.

ARTHUR H. NOBLE, OF PAWTUCKET, RHODE ISLAND, ASSIGNOR TO THEODORE W. FOSTER & BROTHER COMPANY, OF PROVIDENCE, RHODE ISLAND.

LIP-STICK HOLDER.

Application filed November 4, 1926. Serial No. 146,164.

This invention relates to certain new and useful improvements in lip stick holders, and the primary object thereof is to provide a holder which enables a worn lip stick to be easily and quickly removed and a fresh one applied.

A further object of the invention is to provide a holder which has a novel means of simple, compact and economical construction for effecting easy, quick and positive movement of the lip stick into and out of the holder.

The invention has still further and other objects which will be later set forth and manifested in the course of the following description.

In the drawings:—

Fig. 1 is a side elevation of the invention with the parts in inoperative and housed position;

Fig. 2 is a longitudinal sectional view showing the parts in operative position, the lip stick being partly in side elevation;

Figure 3 is a detail side elevation of the lip stick in detached position;

Figure 4 is a fragmentary side elevation of a modified form of attachment of the lip stick to the holder, and

Figure 5 is a view similar to Fig. 4 of a further modified form of the invention.

In proceeding in accordance with the present invention a sleeve-like casing 1 is employed having an intermediate bead 2 that forms a stop for a cap 3. A rotatable circular head 4 engages the base of the casing 1 and carries an inner sleeve 5, the latter being surrounded by an outer sleeve 6, the sleeve 5 having its upper end beaded at 7 and engaged by an inturned flange 8 at the upper end of the casing 1, thereby to hold the sleeve 5 against axial movement while permitting of rotation thereof.

The sleeve 5 is longitudinally slotted at 9 while the sleeve 6 is stationary with respect to the casing and is formed with a spiral slot 10.

A metallic base or ferrule 11 is secured to the base end of a lip stick 13 and is formed with a depressed bayonet-slot 12, the depressing of the metal acting to lock the lip stick to the ferrule, as is apparent from Figure 2.

A tubular carrier 14 slides within the inner sleeve 5 and is formed with a depressed seat 15 that engages in the bayonet-slot 12

thereby to afford, with the latter, a means of detachably securing the lip stick to the carrier.

For the purpose of effecting movement of the carrier 14 into and out of the casing, 60 a transverse pin 16 is secured to the carrier and projects beyond the latter, through slot 9 and into the spiral slot 10. From the foregoing it will be apparent that rotation of the head 4 will effect movement of the 65 carrier and thereby the lip stick into and out of the casing.

In Fig. 4 of the drawings a modified form of connection of the lip stick to the carrier 14 is shown and wherein the latter has 70 threads 17 receiving threads 18 of a ferrule 19, the latter threads being depressed so as to lock the lip stick to the ferrule.

In Fig. 5 a still further modified form of connection is shown and wherein the carrier 75 14" has a contracted tubular and tapered extension frictionally receiving on its interior a tapered ferrule 21 frictionally secured to the lip stick.

In all forms of the invention it will be 80 seen that the lip stick can be easily connected to and disconnected from the carrier.

Having thus described my invention what I claim as new and desire to secure by Letters Patent is:—

In a lip stick holder, an inner sleeve having a head on its lower end and having an axial slot extending throughout its length, said head being formed with a pair of stepped circular peripheral seats, a spirally slotted sleeve surrounding the inner sleeve and seated at its bottom end on the inner seat, the upper end of the inner sleeve being beaded outwardly to overlie the upper end of the second sleeve so as to hold the second 90 sleeve on its seat, said axial slot extending through the said bead, a casing formed of uniform thickness of material surrounding the second sleeve and seated at its bottom on the second seat and having its upper end 100 bent inwardly to overlie and engage the beaded upper end of the inner sleeve, and a lip stick carrier sleeve in the first sleeve having a ferrule removably received in the upper end of the carrier, said inwardly extending bent upper end of the casing providing a stop for the pin. 95 105

In testimony whereof I have hereunto signed my name.

ARTHUR H. NOBLE.
